UNITED STATES PATENT OFFICE

168,469

COMBINED PORTABLE SPOTLIGHT AND
BRACKETJoseph Morgenstern, University Heights, and
Elliott Morgenstern, Cleveland, Ohio

Application June 24, 1952, Serial No. 20,325

Term of patent 14 years

(Cl. D48—20)

To all whom it may concern:

Be it known that we, Joseph Morgenstern and Elliott Morgenstern, citizens of the United States, residing, respectively, at University Heights and Cleveland, in the county of Cuyahoga and State of Ohio, have invented a new, original, and ornamental Design for a Combined Portable Spotlight and Bracket, of which the following is a specification, reference being had to the accompanying drawing, forming part hereof.

Fig. 1 is a side elevational view of a combined portable spotlight and bracket showing our new design;

Fig. 2 is a rear elevational view thereof;

Fig. 3 is a plan view, and

Fig. 4 is a side elevational view on a reduced scale showing the mounting member and the spotlight attachment member separated.

The essential features of our design are shown in full lines.

We claim:

The ornamental design for a combined portable spotlight and bracket, as shown and described.

JOSEPH MORGESTERN.
ELLIOTT MORGESTERN.
